DESIGN FOR A WATER CLOSET BOWL

Antoni J. Lyczak, Kokomo, Ind., assignor to Kokomo Sanitary Pottery Corporation, Kokomo,
Ind., a corporation

Application September 23, 1940, Serial No. 95,297

Term of patent 3½ years

To all whom it may concern:

Be it known that I, Antoni J. Lyczak, a citizen of the United States and a resident of Kokomo, county of Howard and State of Indiana, have invented a new, original, and ornamental Design for a Water Closet Bowl, of which the following is a specification, reference being had to the accompanying drawing, forming part thereof.

In the drawing, Fig. 1 is a front elevational view of a water closet bowl;

Fig. 2 is a rear elevational view thereof;
Fig. 3 is a side elevational view thereof;
Fig. 4 is a top plan view thereof; and
Fig. 5 is a bottom plan view thereof, showing my new design.

I claim:

The ornamental design for a water closet bowl, substantially as shown.

ANTONI J. LYCZAK.
